(57) CLAIM

The ornamental design for a frame assembly, as shown.

DESCRIPTION

FIG. 1 is a perspective view of a frame assembly showing our new design, with the broken line disclosure of a decorative quilt and hardware carried by the quilt forming no part of the claimed design;

FIG. 2 is a perspective view thereof;

FIG. 3 is a front elevational view thereof;

FIG. 4 is a rear elevational view thereof;

FIG. 5 is a right elevational view thereof;

FIG. 6 is a left elevational view thereof;

FIG. 7 is a top plan view thereof; and,

FIG. 8 is a bottom plan view thereof.
